MOTOR DRIVEN RAZOR

Barney R. Nyhagen, New York, N. Y.

Original application July 14, 1936, Serial No. 90,555. Divided and this application June 23, 1938, Serial No. 215,362

4 Claims. (Cl. 30—43)

This invention relates to motor driven razors or hair cutting implements known as dry shavers, and the same is a division of my Patent No. 2,124,985 granted July 26, 1938.

5 The present invention is directed to an improved cutter head for an electric razor or dry shaver in which the movable cutter element is provided with a toothed fin disposed between pairs of toothed flanges on the fixed cutter element and 10 adapted for reciprocation with reference thereto to sever the hair when the toothed flanges are moved over the skin.

15 As a further feature the invention resides in a cutter head of the indicated character in which portions of the fixed cutter head are resilient so as to inherently impinge the confronting faces of the toothed flanges thereof against the opposite side faces of the toothed fin of the movable cutter element to insure a shearing action as the 20 teeth of the fin reciprocate with reference to the teeth of the flanges.

With the above enumerated and other objects in view, reference is now made to the following specification and the accompanying drawing in 25 which there is illustrated an embodiment of the invention.

In the drawing:

Fig. 1 is a side view of a motor driven razor with parts broken away to show the underlying structure.

30 Fig. 2 is a fragmentary enlarged transverse sectional view taken approximately on the line indicated at 2—2 in Fig. 1.

Fig. 3 is an enlarged side view of the cutter 35 head removed from the holder and with parts broken away.

Fig. 4 is a plan view thereof with parts broken away and shown in section.

Referring to the drawing by characters of reference, A designates generally the cutter unit and B the holder member therefor which member consists of a hollow handle constituting a housing for a motor 11 diagrammatically illustrated in the present instance as an electrical motor 40 and having a shaft 12, one terminal of which extends into the groove 13 formed at one end of the handle and is provided with an eccentric or crank pin 14.

The cutter unit A consists of a fixed cutter 50 element 15 and a movable cutter element 16. The fixed cutter element 15 is of generally rectangular shape and is adapted to snugly fit within the groove 13 of the holder member B illustrated in Fig. 1 of the drawing. The fixed cutter element 55 in this instance tapers upwardly and terminates

in a pair of spaced parallel upwardly projecting flanges 17 and is provided with transversely extending notches defining aligned series of teeth 18. The fixed cutter element 15 is provided with a longitudinally extending circular bore 19 and has a longitudinal slot 20 communicating with the bore, with the walls of the slot flush with the inner surfaces of the flanges 17.

The movable cutter element 16 is of cylindrical formation and is mounted for reciprocation 10 within the bore 19 of the fixed cutter element 15 and said cutter element 16 is formed with a preferably integral upstanding fin 21 snugly fitting within the slot 20 and between the flanges 17, the said fin being transversely slotted to provide a 15 longitudinally extending series of cooperating teeth 22 located between the teeth 18 of the fixed cutter element and adapted to cooperate therewith in severing the hair.

The lower side of the main body of the movable cutter element 16 is provided with a transverse groove 23 with which the eccentric pin 14 of the motor shaft 12 is adapted to cooperate to effect reciprocations of the movable cutter element, the lower portion of the fixed cutter element being provided with an opening 24 to receive the terminal of the motor shaft.

The upper opposite side portions of the fixed cutter element 15 are resilient and are so arranged as to inherently impinge the confronting 30 faces of the flanges 17 against the opposite side faces of the fin 21 so as to insure a shearing action as the teeth 22 of the fin reciprocate with reference to the teeth 18 of the flanges 17.

What is claimed is:

1. In a power driven hair cutting implement, a combined holder and actuating member and a cutter unit carried thereby including cooperative cutter elements relatively fixed and movable with reference to said holder and actuating member, 40 the fixed cutter element having a longitudinally extending bore and a longitudinally extending slot communicating with the bore and opening through the upper end of said cutter element with upwardly extending spaced parallel flanges 45 having longitudinally spaced aligned transverse grooves, the movable cutter element having a body slidably fitted within the bore and formed with a radial fin extending through the slot and between said flanges and provided with longitudinally spaced transverse grooves.

2. In a power driven hair cutting implement, a combined holder and actuating member and a cutter unit carried thereby including cooperative cutter elements relatively fixed and mov- 55

able with reference to said holder and actuating member, the fixed cutter element having a longitudinally extending bore and a longitudinally extending slot communicating with the bore and opening through the upper end of said cutter element with upwardly extending spaced parallel flanges having longitudinally spaced aligned transverse grooves, the movable cutter element having a body slidably fitted within the bore and formed with a radial fin extending through the slot and between said flanges and provided with longitudinally spaced transverse grooves, said fixed cutter element being of resilient material adapted to inherently urge the opposite side faces of the slotted portion and the inner surfaces of the flanges into contact with the opposite side faces of the fin.

3. In a power driven hair cutting implement, a combined holder and actuating member and a cutter unit carried thereby including cooperative cutter elements relatively fixed and movable with reference to said holder and actuating member, the fixed cutter element having a longitudinally extending bore and a longitudinally extending slot communicating with the bore and opening through the upper end of said cutter element with upwardly extending spaced parallel flanges having longitudinally spaced transverse grooves, the movable cutter element having a body slidably fitted within the bore and formed with a radial fin extending through the slot and be-

tween said flanges and provided with longitudinally spaced transverse grooves, and said movable cutter element engaging said actuating member for longitudinal reciprocatory movement of the fin between the said flanges.

4. In a power driven hair cutting implement, a combined holder and actuating member and a cutter unit carried thereby including cooperative cutter elements relatively fixed and movable with reference to said holder and actuating member, the fixed cutter element having a longitudinally extending bore and a longitudinally extending slot communicating with the bore and opening through the upper end of said cutter element with upwardly extending spaced parallel flanges having longitudinally spaced transverse grooves, the movable cutter element having a body slidably fitted within the bore and formed with a radial fin extending through the slot and between said flanges and provided with longitudinally spaced transverse grooves, said fixed cutter element being of resilient material adapted to inherently urge the opposite side faces of the slotted portion and the inner surfaces of the flanges into contact with the opposite side faces of the fin, and said movable cutter element engaging said actuating member for longitudinal reciprocatory movement of the fin between the said flanges.
